(57) **CLAIM**

The ornamental design for a loudspeaker, as shown and described.

DESCRIPTION

FIG. 1 is a perspective view of a loudspeaker showing my new design;

FIG. 2 is a front elevational view thereof;

FIG. 3 is a rear elevational view thereof;

FIG. 4 is a side elevational view thereof, the opposite side elevational view being a mirror image;

FIG. 5 is a top plan view thereof;

FIG. 6 is a perspective view of another embodiment of the loudspeaker showing my new design;

FIG. 7 is a front elevational view of the loudspeaker of FIG. 6;

FIG. 8 is a rear elevational view of the loudspeaker of FIG. 6;

FIG. 9 is a side elevational view of the loudspeaker of FIG. 6; the opposite side elevational view being a mirror image; and,

FIG. 10 is a top plan view of the loudspeaker of FIG. 6.

The broken line showings of the letters, geometric shapes and feet form no part of the claimed design.
